UNITED STATES PATENT OFFICE

WILLIAM C. CORTELYOU, OF OBLONG, ILLINOIS

SIGN

Application filed October 18, 1929. Serial No. 400,623.

This invention relates to sign supporting means, the general object of the invention being to provide a frame and a post for supporting the frame, with means whereby sign carrying members can be easily and quickly placed in the frame and removed therefrom and to so construct and arrange the parts that the sign carrying member will not be discolored by rust from the parts of the supporting means.

This invention also consists in certain other features of construction and in the combination and arrangement of the several parts, to be hereinafter fully described, 15 illustrated in the accompanying drawings and specifically pointed out in the appended claims.

In describing the invention in detail, reference will be had to the accompanying drawings wherein like characters denote like or corresponding parts throughout the several views, and in which:—

Figure 1 is an elevation of the invention.

Figure 2 is a section on line 2—2 of Figure 1.

Figure 3 is an end view of Figure 2.

Figure 4 is a view of the inner edge of one of the side pieces of the frame.

Figure 5 is a section on line 5—5 of Figure 4.

In these views, A indicates the supporting post for the device and B indicates the frame supported by the post and holding the sign carrying members. This frame is composed of the upper and lower horizontal bars 1, each of which is formed with a centrally arranged longitudinally extending groove 2 in its outer edge and a centrally arranged transverse hole 3 for receiving a part of the post, and the end bars 4 which contact the ends of the bars 1. Rods 5 pass through the grooves 2 and through holes in the end bars 4 and have their ends threaded to receive the nuts 6. These rods also pass through holes formed in the post A. Thus these rods and the nuts on their threaded ends hold the parts of the frame together and also hold the frame on the post. The inner edges or faces of the bars 1 are formed with the grooves 7 which form

guideways for the sign carrying plates or members 8 and it will be seen that by removing the nuts at one end of the frame, the end bar at this end of the frame can be removed so that the members 8 can be slid 55 in the guideways or removed therefrom, so that the sign can be easily and quickly changed whenever desired. Of course, if desired, but one of the members 8 can be used.

The post A is composed of the two sections 9 and 10, the lower section 10 being of greater diameter than the upper section 9, and the two sections are connected together by the coupling 11. The lower end of the section 10 is adapted to be placed in a hole in the ground and anchor plates 12, arranged as shown in Figures 1 and 5, are bolted to the section which is adapted to be placed in the ground and thus prevent movement of the post. By making the metal parts of non-rusting material, there is no danger of the sign being discolored by rust streaks.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. Sign supporting means comprising a post, a frame consisting of a pair of side bars 85 and a pair of end bars, said side bars having openings therein through which the post passes, rods connecting the end pieces with the side pieces and passing through the post and nuts on the ends of the rods for detachably holding the end pieces against the ends of the side pieces.

2. Sign supporting means comprising a post, a frame consisting of a pair of side bars and a pair of end bars, said side bars having 95 openings therein through which the post passes, rods connecting the end pieces with the side pieces and passing through the post, nuts on the ends of the rods for detachably holding the end pieces against the ends of 100

the side pieces, said side pieces having grooves in their inner faces for receiving a sign carrying member.

3. Sign supporting means comprising posts, a frame supported thereby and consisting of a pair of side pieces and a pair of end pieces, the side pieces having holes therein through which the post passes and said side pieces having longitudinally extending grooves in their outer faces, rods resting in the grooves and passing through the end pieces, nuts on the ends of the rods for holding the end pieces against the ends of the side pieces, said rods also passing through the post for holding the frame on the post and the side pieces having grooves in their inner faces for receiving the edges of a sign carrying member.

In testimony whereof I affix my signature.

20 WILLIAM C. CORTELYOU.
